UNITED STATES PATENT OFFICE

2,608,216

LOOM HARNESS

John J. Kaufmann, Elkins Park, Pa., assignor to
Steel Heddle Manufacturing Company, Philadelphia, Pa., a corporation of Pennsylvania

Application May 24, 1949, Serial No. 94,958

4 Claims. (Cl. 139—92)

1

This invention relates to loom harness and it relates more particularly to the construction and arrangement of frames, and the parts carried thereby, for supporting the heddles which separate the warp ends in successive sheds for the passage of the shuttle therebetween to effect the weaving operation.

Heretofore most of the frames used in looms for supporting the heddles were made with top and bottom rails or shafts of wood connected at their ends by side struts usually made of flat metal strips secured to the ends of the top and bottom rails or shafts.

By reason of the present availability of light metal alloys of aluminum and the like it has been suggested to substitute, for the top and bottom rails or shafts made of wood, rails or shafts made of light metal alloys which are extruded through dies in the desired shape in cross-section. However, such rails or shafts are usually made hollow and certain difficulties have arisen in the use of such metallic rails or shafts, principally in connection with the means for attaching the actuating cords or straps thereto, and also in connection with the means for supporting the heddle rods in the frames intermediate the ends thereof.

The principal object of the present invention is to provide a novel and efficient form of heddle frame in which the top and bottom rails or shafts may be made of extruded hollow metal shapes, and which frame is so constructed and arranged as to provide improved means for mounting the hooks or other attaching devices to which the cords or straps for actuating the frames may be secured, and also to provide improved means for supporting the heddle rods intermediate the ends thereof.

A further object of the invention is to provide a loom harness frame, of the character aforesaid, in which the heddles mounted on the supporting rods may have complete freedom to move from one end to the other of the frame, so that the entering of the warp may be done by means of automatic drawing-in machines.

The nature and characteristic features of the invention will be more readily understood from the following description, taken in connection with the accompanying drawing forming part hereof, in which:

Figure 1 is a front elevation of a loom harness frame embodying the main features of the present invention;

Fig. 2 is a transverse vertical section of a portion thereof, enlarged, taken on the line 2—2 of Fig. 1; and

2

Fig. 3 is a fragmentary perspective view of certain of the parts of the harness frames, the same being shown in separated relationship to more clearly illustrate the invention.

It should, of course, be understood that the description and drawing herein are illustrative merely, and that various modifications and changes may be made in the structure disclosed without departing from the spirit of the invention.

Referring to the drawing, the top and bottom rails or shafts 10 of the frame are connected at their ends by means of side struts 11. The side struts 11 may be, and preferably are, made of wood, whereas the top and bottom rails or shafts 10 are made of extruded metal shapes, preferably hollow, whereby they are provided with relatively thin side walls 12 and inner marginal portions 13, somewhat thicker than the side walls 12.

The outer marginal portion 13 of each of the top and bottom rails 10 is provided with a T-shaped groove 15 extending from end to end of the rail 10, so that there is thus provided means for mounting at any required locations in the length thereof, wherever it may be desired to mount the same, two or more hooks 16 for connecting the actuating cords or straps (not shown) which are used for raising and lowering the frame in the loom in the usual and customary manner.

Through the provision of the T-shaped groove 15 in the outer marginal portion 13 of each of the top and bottom rails 10, a wide variety of attaching devices may be employed for connecting the actuating cords or straps. As shown, the same may comprise the hooks 16, which are ordinary hooks having threaded shank portions 17, and having nuts 18 and 19 threaded thereon. One of said nuts 18 is located in the groove 15 and the other of said nuts 19 bears against the outer marginal surface of the rail. This arrangement permits the adjustment of the hooks 16 in the frame for levelling and positioning the frames in the loom.

The threaded shank portion 17 of the hook may extend inwardly into the hollow interior of the rail through an aperture 20 drilled in the metal of the rail which is provided at 21 between the T-slot and the hollow interior of the rail thereby providing for a considerable range of vertical adjustment of the hooks in the rails.

Extending inwardly from the inner marginal portion of each rail or shaft 10 toward the center of the frame is a longitudinal rib or flange 22 to which there is secured, preferably by rivets 23, at suitable locations intermediate the ends of the frame, bracket members 24. Each of said bracket

members 24 comprises a suitably shaped plate having a longitudinal slot 25 therein and provided at places with enlarged portions 26.

The heddle supporting rods 27 extend from end to end in the frame. The ends of the heddle rods 27 are preferably positioned in recesses or slots 28 in the side struts 11 and are normally retained therein by means of spring hook members 29 which may be of any preferred type such, for instance, as those shown in my previous application for Letters Patent, filed April 17, 1947, Serial No. 741,972, whereby the heddle rods may be conveniently detached at the ends from the frame for the purpose of adding or removing heddles, either for the replacement of broken heddles or for increasing or decreasing the count of the warp in the cloth to be woven.

Each of the heddle supporting rods 27 is provided, at the proper locations, with members 30 shaped to pass through the enlarged portions 26 of the slots 25 in the bracket members, but which, when a particular heddle rod 27 is slid longitudinally, serve to lock the rod against lateral movement or flexing at such location. The members 30 are secured to the heddle rods by spacers 31.

The heddles 32 are preferably of the type shown in Figs. 2 and 3 of my previous Letters Patent No. 2,047,511, whereby the same may have complete freedom of movement from end to end of the frame, and thus permit the frames to be used in installations in which the warp is entered by automatic drawing-in machines.

I claim:

1. A loom harness frame comprising hollow metallic top and bottom rails connected at their ends by side struts, each of said rails having a longitudinal rib portion projecting inwardly toward the center of the frame, heddle rods having their end portions detachably secured in the side struts, bracket members secured to said ribs at locations intermediate the ends of the frame, means for interlocking portions of the heddle rods with portions of said bracket members, and heddles mounted on the heddle rods.

2. A loom harness frame comprising hollow metallic top and bottom rails connected at their ends by side struts, each of said rails having a longitudinal rib portion projecting inwardly toward the center of the frame, bracket members

secured to said ribs at spaced locations intermediate the ends of the frame, heddle rods having their end portions detachably secured in the side struts, means for interlocking portions of the heddle rods with portions of said bracket members upon longitudinal movement of the heddle rods, and heddles mounted on the heddle rods.

3. A loom harness frame comprising hollow metallic top and bottom rails connected at their ends by side struts, each of said rails having a longitudinal rib portion projecting inwardly toward the center of the frame, bracket members secured to said ribs at locations intermediate the ends of the frame, said bracket members having slotted portions, heddle rods having their end portions detachably secured in the side struts, devices carried by the heddle rods interlocking upon longitudinal movement of the heddle rods with the slotted portions of said bracket members, and heddles mounted on the heddle rods.

4. A loom harness frame comprising hollow metallic top and bottom rails connected at their ends by side struts, each of said rails having a longitudinal rib portion projecting inwardly toward the center of the frame, bracket members fixedly secured to said ribs at spaced locations intermediate the ends of the frame, said bracket members having slotted portions, heddle rods having their end portions detachably secured in the side struts, devices carried by the heddle rods interlocking upon longitudinal movement of the heddle rods with the slotted portions of said bracket members, and heddles mounted on the heddle rods.

JOHN J. KAUFMANN.
